FIG. 4.

The diagram illustrates a vacuum tube circuit. A power source C is connected to the circuit. The circuit consists of several stages: a grid leak oscillator (labeled A), a pentode stage (labeled B), and a final stage (labeled C). The circuit is complex, with multiple vacuum tubes and various components labeled with letters A through Z . The connections are shown with dashed lines, indicating the flow of current and signals between the different stages and components.

UNITED STATES PATENT OFFICE.

WILLIAM STROUDLEY, OF BRIGHTON, COUNTY OF SUSSEX, AND EDWARD JOHN HOUGHTON, OF PECKHAM, COUNTY OF SURREY, ENGLAND.

APPARATUS FOR ELECTRIC LIGHTING ON RAILWAY-TRAINS.

SPECIFICATION forming part of Letters Patent No. 288,888, dated November 20, 1883.

Application filed September 3, 1883. (No model.) Patented in England May 23, 1883, No. 2,579.

To all whom it may concern:

Be it known that we, WILLIAM STROUDLEY, engineer, and EDWARD JOHN HOUGHTON, electrical engineer, subjects of the Queen of Great Britain, and residing, respectively, at Brighton, in the county of Sussex, England, and 1 Pilkington Road, Peckham, in the county of Surrey, England, have invented certain Improvements in Means and Apparatus for Electric Lighting on Railway-Trains and other Vehicles, also partly applicable for the production and distribution of electric currents generally, (for which we have obtained a patent in Great Britain, No. 2,579, dated May 23, 1883,) of which the following is a specification.

Our invention relates, mainly, to improved means and apparatus for electric lighting on railway-trains and other vehicles by means of dynamo-electric or magneto-electric machines and electric accumulators, reservoirs, or secondary batteries, the dynamo-electric machines being driven by the motion of the train, and thus made to charge the accumulators from which the electric lamps are supplied.

We will describe our invention with reference to the accompanying drawings, Figure 1 of which is a side elevation, partly in section, and Fig. 2 an end elevation, (drawn to a larger scale,) of a dynamo-machine arranged according to our invention. Fig. 2^a is a partial view in section on line x x, Fig. 1, and in elevation, looking in the direction of the arrow. Fig. 2^b is a diagram illustrating a modified arrangement for automatically completing the circuit through the accumulators to be charged when the electrical machine attains or falls below the normal speed. Fig. 3 is a diagram of a modified arrangement for reversing the commutator-brushes, and Fig. 4 is a diagram showing a plan for charging the field-magnet coils from the lamp-circuit and a system of working with two sets of accumulators. Figs. 4^a and 4^b are plans of a switch arranged for our system of distribution of currents.

According to one of our improvements, we effect the automatic reversal of the commutator-brushes of the dynamo or magneto elec-

tric machine in the reversal of the motion of the machine, according as the train is traveling in one direction or the other, so that the collection and storing up of the electric energy will be effected under all circumstances. The commutators are arranged in two pairs, (marked P and P² in Fig. 2,) carried by swing-frames, so that either the two marked P or the two marked P² are in contact with the commutator, according to the direction in which the vehicle or train is running. For this purpose the axis of the commutator A carries a pulley, B, fixed thereto, round which pulley passes a gut, b, whose one end is attached at c to a sleeve, C, on the axis p of the upper commutator-brushes. This sleeve C has an arm, D, projecting up from it, and on this arm is a sliding piece, d, to which the other end of the gut b is attached, the said piece d being pushed upward by a spring, d', with a force sufficient to cause the gut b to be held tight round the pulley B, so that when the said pulley is rotated in one or the other direction it causes also the sleeve C, with its arm D, to turn somewhat in one direction or the other. The arm D has its upper end cranked and pivoted to a swinging rod, E, pivoted at its upper end by a pivot, e, and having a hook, e', at its lower end, embracing a bar, f, on the upper swinging frame of the brushes, so that by the above-described movement of the sleeve C and its arm D in one or the other direction the swinging rod E is slid, with its hook e', to the one or the other end of the said bar f, so that if the said rod E be now lifted it will raise up the swinging frame of the brushes in one direction or the other, thereby bringing the one or the other pair of brushes, P or P², into contact with the commutator, the upper and lower swinging frames, G G², being connected together by a link, g, so as to be made to move simultaneously. When not acted upon by the swinging rod E, the swinging frames G G² are maintained in an intermediate position, as shown in Fig. 2, (in which all the brushes are out of contact with the commutator,) by means of a flat spring, h, bearing against a flat surface on the lower swinging

frame. The making of contact of one or other of the pairs of brushes with the commutator A is, according to another of our improvements, only made to take place after the field-magnet coils are charged. For this purpose, according to one arrangement, the armature-axis of the magneto-electric machine, by a band passing over the pulleys I J, drives a centrifugal governor, K, whose sleeve actuates one end of a double-ended lever, L, turning upon an adjustable center, l, its other end being attached to a block, M, sliding on a vertical bar, N, which also carries a second sliding block, Q, above the first one, the said block Q carrying the pivot e of the swinging rod E of the brush-frames. Between the two sliding blocks is a helical spring, r. The lever L is held down by a spring or weight, (a spring is shown at s,) so that the governor K can only begin to move it when the armature of the magneto-electric machine has attained a certain speed. When the said lever L begins to move, it raises the lower sliding block, M, and this, through the helical spring r, also raises the upper block, Q, thus raising the before-mentioned swinging rod E, and thus tilting the carrier G, and, through the rod g, also the carrier G², so as to bring either the pair of brushes or rubbers P or the pair P² into contact with the commutator, as hereinbefore mentioned, so that the current flows to the storing-batteries in the proper direction, whichever way the train or vehicle may be traveling.

In place of a centrifugal governor being employed, the machine may be arranged to run on a short circuit, in which is an electro-magnet so arranged that when the electro-motive force has increased beyond a certain limit the magnet will actuate a switch and throw the batteries in; but the governor will be found the more convenient plan.

The arrangement with the magnet is shown in Fig. 2^b, in which 5 is an electro-magnet, 7 a switch-lever which carries the armature 6 to the magnet 5, and 8 and 9 contact-plates connected, the former with a short-circuiting branch or shunt, 10, the latter with the branch 11 including the batteries to be charged. The positive wire 12 from the electrical machine 5 is connected through the coils of magnet 5 with the switch-lever 7. In the position shown the machine discharges into the short circuit 10, the attraction of magnet 6 being insufficient to overcome the force of the retractile spring 13. When, however, the machine attains its normal speed, the current, and consequently the attraction of magnet 5, has increased sufficiently to shift the switch-lever 7 into contact with the plate 9, thus breaking the short circuit and putting the electrical machine in connection with the accumulators to be charged.

According to another of our improvements, the exciting-current for the field-magnets of the machine is derived from the lamp-circuit,

and the contact for this, as also that for the charging-circuit to the secondary batteries, is only made after the commutator-brushes are brought into action, and after the machine has attained a certain speed. For this purpose the before-mentioned lever L carries at one point a contact-block, t, so arranged that when the lever L, after having put the brushes on the commutator, is raised still higher by the governor K, consequent on a further increase of speed of the machine, it compresses the helical spring r between the two sliding blocks M and Q, and at the same time brings the contact-block t first against contact-pieces, as at u, (see Figs. 1 and 2^a,) which connect up the circuit of the exciting-current for the field from the lamp-circuit, and thereafter against other contact-pieces, as at v, that connect up the charging-circuit from the machine to the batteries. These contacts are maintained so long as the normal speed of the magneto-electric machine is maintained. As soon as the speed drops, the lever L in falling first disconnects the charging-circuit, then the exciting-circuit, and, lastly, brings the brushes out of contact. t² is a piece of insulating material at the top of the contact-block t, upon which the contact-pieces u v bear when the machine is out of action.

According to another modification, (illus. 95) illustrated by the diagram, Fig. 3,) we mount loosely upon the commutator-axis a metal beam, U, (insulated from the said axis,) to the opposite ends of which beam U are fixed sockets or holders V, insulated from the beam U and carrying the brushes or rubbers W, which in this case are made up of rectangular pieces of sheet-copper, which are kept continuously against the commutator by springs w w² in the sockets V. The beam U has spring-arms Z projecting 100 from the back thereof between the prongs of the forked contact-pieces Z*, which form the terminals of the branch derived from the lamp-circuit for exciting the dynamo. (See Fig. 4.) When the armature is at rest or is revolving slowly, the beam U is held in mid-position by the flat spring h, which bears upon the flattened portion of a boss on the beam, so that the spring-arms Z are clear of both prongs, as shown, and the exciting-circuit is open. When, however, the friction becomes sufficient by reason of rotation of the armature and commutator, it carries the beam U to the right or left, according to the direction of rotation, and closes the exciting circuit or branch, so that the field is included in the circuit of the accumulators discharging. Spring-arms X X² project from either side of the sockets W. As the speed of the armature and the friction between the commutators and the brushes further increase, the beam U is dragged around until (the arms Z bending) it brings the arms X or X² into contact with screws Y, according to the direction in which the armature is revolving. The circuit of the accumulators to 125

be charged is thus completed in the proper manner for charging, whichever way the armature may turn.

According to another improvement, (represented by Fig. 4,) we arrange a dynamo or magneto electric machine, B, to operate in combination with two sets of accumulators, C and C², and a circuit to lamps D, by means of a special commutator, A, having contacts so arranged that in one position of the said commutator it connects the dynamo or magneto machine B with the one set of accumulators C or C², so as to charge them, while at the same time it connects the other set of accumulators, which have been previously charged, with the lamp-circuit. When this first-named set of accumulators have become charged and the last-named set are exhausted, the commutator A is turned so as to connect the magneto or dynamo machine B with the exhausted set and the lamp-circuit with the charged set. The commutator A has for this purpose, first, two contacts for the two poles of the charging-circuit of the magneto or dynamo machine B; secondly, two contacts for each of the accumulators which are connected alternately with those of the magneto or dynamo machine B; and, thirdly, two contacts for the circuit of the lamps D, which are alternately connected with the two contacts of one or other of the sets of accumulators C or C². The circuits can be readily traced from the diagram, Fig. 4, and the plan views, Figs. 4^a and 4^b, of a switch arranged for our system of currents. The barrel has contacts A and B and contact-springs C. The contact-pieces A are of a length to extend from spring to spring of a pair, as shown in Fig. 4^a. The contact-pieces B, on opposite sides, are connected metallically with each other, as shown at b, Fig. 4^a. The direction of the currents is shown by the dotted lines. In the position, Fig. 4^a, the current from the dynamo enters at 1, passes from 2 to the set of accumulators being charged, and then passes across 3 and 4 back to the dynamo. The current from the accumulators discharging passes in at 1^a, out at 2^a to the lamps and field-magnets, and back through 3^a and 4^a to the accumulator. When second set of accumulators is exhausted and the first set charged, the barrel is turned to the position, Fig. 4^b, the current from the dynamo enters at 1 and passes at 1^a to store the second set of accumulators, thence passing by 4^a and 4 back to the dynamo. The current from the other set of accumulators previously charged passes in at 2, and out at 2^a to the lamps and field-magnets, and then by 3^a and 3 back to the accumulators. The exciting-current for the field of the generating-machine is, as before, derived from the lamp-circuit. E is a switch by which the current to the lamp-circuit can be turned on or off.

Although we have described our improvements as specially applicable to electric lighting in railway-trains and other vehicles, yet it

will be readily understood that the arrangements for regulating, for making and breaking contacts, and for distributing the currents are also applicable to other electrical purposes. 70

We claim—

1. In apparatus for generating electricity from motive power applied in different directions, distinct sets of commutator brushes or rubbers arranged upon swinging carriers, in combination with a swing-arm, E, which is brought into position to bring the one or the other set of brushes into contact with the commutator, according to the direction of rotation, substantially as hereinbefore described. 80

2. In apparatus for generating electricity from motive power applied in different directions, a governor acted upon from the revolving armature, so as to bring one or other of distinct sets of commutator brushes or rubbers into contact with the commutator to supply the current always in the proper direction, in whichever direction the motive power may be applied, substantially as hereinbefore described. 90

3. The combination, with a dynamo-electric machine and a circuit supplied from a separate generator for exciting the field thereof, of a governor with contacts and connections for completing, successively as the speed of the armature rises, the said exciting-circuit and the circuit into which the dynamo discharges, substantially as described. 95

4. The combination, with a dynamo-electric machine, a set of accumulators to be charged, conductors for connecting said accumulators in circuit with the dynamo, and a circuit supplied from a separate generator for exciting the field, of a governor and contact-makers operated thereby for completing successively, 100 as the speed of the dynamo rises, the said exciting-circuit and the circuit for charging the accumulators, substantially as described. 105

5. In apparatus for lighting by electricity, the dynamo-electric machine, the lamps, a charging-circuit including the armature of said machine, and a consumption-circuit including the lamps and the field of said machine, in combination with two sets of accumulators included, the one in the charging and 110 the other in the consumption circuit, and a switch for changing the circuit-connections, so that each set is included alternately in the charging and consumption circuits, and while one set is charging the other is discharging, 115 substantially as described. 120

6. The combination, with a primary generator, two sets of accumulators, a charging-circuit and a consumption-circuit, of a switch for connecting the accumulators at will in either circuit, said switch having separate contact-plates for the two poles of each circuit, and also of each set of accumulators, so that the circuits are kept independent at the switch, substantially as described. 130

7. The combination, with the armature and commutator, and devices for causing the cur-

rent in the exterior circuit to flow in the same direction, whichever way the armature revolves, of a governor connected with and acting upon the aforesaid devices, for keeping 5 open the said exterior circuit until the armature has acquired speed, substantially as described.

8. The combination, with the commutator and movable brushes therefor, of a governor 10 connected with said brushes for bringing them into position to take off the current when the armature has attained a certain speed, substantially as described.

9. The combination, with the revolving armature and commutator, of the movable 15 brushes or rubbers, means for conducting away the current from the brushes, and friction devices for controlling the position of the said brushes or rubbers, so that the current 20 will be taken off in the same direction, whichever way the armature turns, substantially as described.

10. The armature, the commutator, and the two sets of brushes or rubbers, in combination with mechanism for bringing the one set or 25 the other into contact with the commutator, according to the direction of rotation of the armature, the brushes on the same side of the commutator being insulated from each other, so that they may constitute separate poles of 30 the exterior circuit, substantially as described.

In testimony whereof we have signed our names to this specification in the presence of two subscribing witnesses.
